CONTACT FEEDING MECHANISM

William M. Spry, deceased, late of Revere, Mass.,
by Alice M. Spry, executrix, Revere, Mass., as-
signor to The Peerless Machinery Company,
Boston, Mass., a corporation of Massachusetts

Application August 13, 1940, Serial No. 352,391

3 Claims. (Cl. 218—15)

This invention relates to a mechanism for feeding elongate contacts to an eyelet-setting mechanism and is in the nature of an improvement upon the machine disclosed in Patent No. 1,850,052.

In the manufacture of radio and similar apparatus, contacts are used which are made of an elongate flat piece of metal provided with an integral eyelet barrel projecting from one face of the contact adjacent one end thereof and the present invention relates primarily to an improved mechanism for automatically and continuously feeding such contacts from a hopper into a raceway and delivering them to the eyelet-setting mechanism in a predetermined alignment or position, and more particularly to an improved raceway which prevents the contacts from becoming clogged at the lower end of the raceway.

The primary object is the provision of an improved raceway which ensures delivery of the contacts one at a time from the delivery end of the raceway and which prevents clogging or double-feeding thereof.

Other objects will be apparent from a consideration of the accompanying drawing in which one embodiment of the invention is illustrated.

In the drawing:

Fig. 1 is a side elevation of a machine embodying the invention and showing the feeding mechanism and a portion of the top set of the setting mechanism;

Fig. 2 is an enlarged plan view of the hopper with the cover removed and parts broken away and shown in section, looking in the direction of the arrows 2—2 of Fig. 1;

Fig. 3 is an enlarged elevation of the lower end of the raceway looking in the direction of the arrows 3—3 of Fig. 1;

Fig. 4 is an enlarged plan view looking upwardly at the raceway in the direction of the arrows 4—4 of Fig. 1;

Fig. 5 is an enlarged plan view similar to Fig. 4, but showing one contact being withdrawn from the end of the raceway;

Fig. 6 is an enlarged section taken on the line 6—6 of Fig. 1;

Fig. 7 is an enlarged partial elevation looking in the direction of the arrows 7—7 of Fig. 6;

Fig. 8 is an enlarged partial elevation similar to Fig. 7, but showing no contacts on the runway; and

Fig. 9 is a section on the lines 9—9 of Fig. 2.

The contacts 15 shown in plan in Fig. 4 and in side elevation in Fig. 7 comprise an elongate

plate 16 with an integral eyelet barrel 17 projecting from one face adjacent one end thereof. The contacts are also provided with an integral prong 18 projecting from one face. This prong lies adjacent one edge of the insulating material after the contact has been affixed thereto and it serves to hold the contact against displacement with respect to the insulating material.

An integral base plate 21 (Figs. 1 and 2) forms 10 the bottom of the hopper and the base of the raceway. The hopper side wall 22 is attached to the base plate and a removable cover 23 forms 15 the top of the hopper. A pair of filter plates 25, 25^a are secured to the raceway portion of the base plate 21 and their adjacent edges are spaced apart a slightly greater distance than the width of the contact (Fig. 2) and these plates are thicker than the thickness of the contact plate member 16. A pair of face plates 26, 26 are secured respectively to the outer faces of the filter plates 25 and their adjacent edges are spaced apart a distance slightly greater than the diameter of the eyelet barrel (Fig. 2). Screws 27 may be used to secure both the face plates and the filter plates to the base plate in superimposed relation. Thus a raceway is provided which has a runway permitting a contact to slide therein in the direction of the longitudinal axis of the contact.

30 The hopper and raceway are supported for slight pivotal movement about the axis 30 (Fig. 1) so that the lower end of the raceway may be swung inwardly beneath the spindle 31 of the top set 32, and after the spindle continues downwardly and engages the interior of an eyelet barrel holding same frictionally thereon, the lower end of the raceway may be swung outwardly or retracted from the spindle to permit the top set and spindle to continue their downward movement and to complete the eyelet affixing and clenching operation in conjunction with the bottom set (not shown).

40 A transverse opening 35 (Fig. 9) of inverted T-shape is provided through the hopper wall 45 to permit the passage of a contact therethrough. The base of the longitudinal portion of this opening 35 is located in the plane of the bottom of the hopper and the opening is located above the lowermost point of the surface of the hopper bottom, so that contacts in the hopper must be moved upwardly along the bottom of the hopper to reach the opening (see Figs. 1 and 2). The upper end of the raceway communicates with this opening 35, the ends of the filter plates 25 and 25^a being in substantially the same plane as

the longitudinal portion of the opening and the adjacent sides of the face plates 26 near their ends being substantially parallel to the sides of the stem portion of said opening.

A stop 36 projects from the inner side of the hopper wall and is secured to the wall by screws 37 (Fig. 9). This stop 36 is located adjacent one side of the stem portion of the opening 35 and slightly above the adjacent longitudinal portion of said opening, as shown in Fig. 9.

A brush 40 (Fig. 2) is secured to the shaft 41 adjacent one end thereof and said shaft extends transversely through the bottom of the hopper and is mounted for rotation in suitable bearings. A gear 42 (Fig. 1) is secured to the other end of the shaft 41. A rack 43 is mounted for movement to and fro in the guide 44; the teeth of the rack meshing with the teeth of the gear 42. As the rack 43 is actuated to and fro, its teeth mesh with the gear teeth and rotate the gear 42, shaft 41 and brush 40 first in one direction and then in the opposite direction. The rack is preferably operated to cause the brush to rotate substantially 207° first in one direction and then in the opposite direction.

Upon movement of the brush in the direction of the arrow in Fig. 2, contacts in the hopper are moved upwardly along the bottom of the hopper toward the hopper opening 35. As a contact reaches the opening, the edge of its plate member enters the longitudinal portion of the opening and rests on the end of the lower filler plate. As the contact moves still farther upwardly to a position where the eyelet barrel is opposite the stem portion of the opening 35, the eyelet barrel strikes the stop 36 and the contact is brushed eyelet-end foremost into the upper end of the raceway, as shown in Fig. 2. The tail of the contact is swung under the stop 36 as the contact enters the raceway (see Fig. 2).

The inner edge of the filler plate 25^a adjacent the hopper opening 35 is spaced from said opening a distance less than the total length of a contact. Thus when a contact enters the raceway tail-end foremost, the said inner edge of the filler plate 25^a engages the end of the contact tail, the upper corner of the lower filler plate 25 engages the lower edge of the contact, and the stop 36 engages the eyelet barrel 17, thus preventing the contact from being swung around the corner of the lower filler plate 25 into the raceway. As the brush is rotated in the opposite direction, it strikes that portion of the contact which remains within the hopper and pushes it downwardly to withdraw it from the opening 35 and return it to the hopper; thus when the brush is again rotated in the initial direction, contacts have free access to said opening.

Thus the stop 36 cooperates with the raceway and particularly with the lower edge of the opening and the filler plate 25^a of the raceway to permit contacts to enter the raceway only eyelet-end foremost. The shape of the opening in the hopper wall permits the contacts to enter the raceway only eyelet barrel uppermost.

As the contacts enter the runway of the raceway, they slide by gravity to the lower end thereof.

The lower end of the raceway is provided with a spring clip 50 (Figs. 3, 4, 5 and 6) which is pivotally secured at one end to the raceway by a bolt or screw 51. The tip of the clip receives and holds the lowermost contact in the raceway, the eyelet barrel of the contact resting against the face of the tip of the clip as shown in Fig. 75

4. The spring 52 tends to keep the clip in the position shown in Fig. 4 with the edge of the clip resting against the adjacent edge of the face plate 26. After the spindle 31 has entered 5 the eyelet barrel of the lowermost contact, the lower end of the raceway is moved outwardly away from the spindle and hence the spindle retains the end contact by frictional engagement within the eyelet barrel. The clip 50 is rotated 10 slightly around the pivot 51 and away from the edge of the plate 26, thus allowing the lowermost contact to pass out of the raceway as the raceway moves away from the spindle (see Figs. 1 and 5).

15 As soon as this contact has left the raceway, the spring 52 forces the clip 50 back into its original position with its tip across the runway.

20 Affixed to the clip 50 is a separating finger 55. This finger rests in a channel 56 which is provided integral with the clip 50 and the finger is 25 adjustably affixed therein by screws 57. The finger 55 is provided with an upwardly bent flange 60 at its free end. In the normal position of the clip 50 as shown in Fig. 4 the flange 60 of the finger 55 does not engage any contact eyelet barrel, but as the lowermost contact leaves the runway (see Fig. 5) and the clip is rotated by that 30 contact barrel in a clockwise direction (looking at Fig. 5), the finger 55 rotates in the same direction with the clip, and the flange 60 then 35 engages the eyelet barrel of the next succeeding contact (Fig. 5) so that only one contact can leave the runway during each rotation of the clip 50. When the clip returns to its normal 40 position (shown in Fig. 4) the flange 60 is rotated out of engagement with the eyelet barrel and the contact slides a short distance down the raceway until the eyelet barrel rests against the tip of the clip 50. This device ensures the removal of contacts one at a time from the end 45 of the raceway.

50 In the normal operation of the feeding mechanism there are always several contacts at the lower end of the raceway and these contacts have a tendency to overlap, as shown in Fig. 7, the prong 18 entering the eyelet barrel of the next succeeding contact. To eliminate clogging, a cavity 70 is provided in the face of the facing strips 26 adjacent the end of the raceway, as 55 shown in Figs. 6, 7 and 8. This cavity is slightly shorter than the length of the contact and the lower end of the cavity gradually slopes upwardly to the normal plane of the face of the facing strip 26, thereby serving to direct the forward end of each contact out of the cavity. As shown in Fig. 10, this cavity serves to lift the prong 18 out of engagement with the next succeeding eyelet barrel and to permit the end contact to slide freely to the end of the raceway.

60 The operation of the machine is fully automatic; the lower end of the raceway is automatically rotated beneath the spindle 31 and then away from the spindle in timed relation to the downward movement of the spindle and the top set. Thus the continuity of feeding of contacts to the raceway and of removal of contacts one by one from the end of the raceway is of great importance in connection with speedy and continuous affixing of contacts to the insulating material.

65 What is claimed is:

70 1. A raceway for feeding elongate eyelet contacts to an eyelet-setting mechanism, comprising a backing member having a face for engagement with one face of the contact, an elongate

facing member having a face spaced from said face of said backing member, and a cavity formed in said face of said facing member adjacent the delivery end of the raceway, said cavity being adapted to permit the forward end of a contact to temporarily drop downwardly into said cavity.

2. A raceway for feeding elongate eyelet contacts to an eyelet-setting mechanism, comprising a backing member having a face for engagement with one face of the contact, an elongate facing member having a face spaced from said face of said backing member, and a cavity formed in said face of said facing member adjacent the delivery end of the raceway, said cavity being shorter than the length of a contact and being adapted to permit the forward end of a contact to temporarily drop downwardly into said cavity.

3. A raceway for feeding elongate eyelet contacts to an eyelet-setting mechanism, comprising a backing member having a face for engagement with one face of the contact, an elongate facing member having a face spaced from said face of said backing member, and a cavity formed in said face of said facing member adjacent the delivery end of the raceway, said cavity being adapted to permit the forward end of a contact to temporarily drop downwardly into said cavity, said cavity having a forward end which slopes gradually upwardly to the normal plane of said face of the facing member thereby to direct said forward end of the contact out of the cavity.
